DESIGN FOR AN AIR CIRCULATOR

Herman C. Hueglin, Chicago, Ill., assignor to Federal Merchandise Company, Chicago, Ill., a corporation of Illinois

Application October 10, 1934, Serial No. 53,538

Term of patent 7 years

To all whom it may concern:

Be it known that I, Herman C. Hueglin, a citizen of the United States, residing at Chicago, in the county of Cook and State of Illinois, have invented a new, original, and ornamental Design for an Air Circulator, of which the following is a specification, reference being had to the accompanying drawing, forming a part thereof.

In the drawing, the single figure is a perspective

view of an air circulator embodying my present invention.

I claim:

The ornamental design for an air circulator, as shown.

In witness whereof, I hereunto subscribe my name, this 5th day of October, 1934.

HERMAN C. HUEGLIN.
